GASEOUS ELECTRIC DISCHARGE LAMP

Howard Haynes, Willoughby, and Lynn S. Ickis,
Jr., East Cleveland, Ohio, assignors to General
Electric Company, a corporation of New York

Application Sept. 30, 1944, Serial No. 556,559½

12 Claims. (Cl. 176—125)

1 Our invention relates to gaseous electric discharge devices.

Certain types of gaseous electric discharge lamps, such as hot or thermionic cathode fluorescent lamps now in extensive use and employing activated filamentary electrodes at the ends of an elongated tubular envelope, are started by passing current through the electrodes to preheat them before application of a potential higher than the operating potential of the lamp to initiate the discharge between the electrodes. This type of lamp is incapable of starting at the voltages applied thereto in the event the electrodes have become deactivated. Repeated flashing of the lamp in unsuccessful attempts to start is obviated by employing a suitable cut-out switch which opens the circuit therethrough, so that the lamp merely remains unlighted to indicate the need for replacement.

However, certain other types of lamps employing activated thermionic electrodes are started "cold," that is, the electrodes are not preheated as described above. This type of starting necessitates the use of higher voltages, and the lamps do not extinguish themselves at the end of life as determined by electrode deactivation, particularly on high voltage circuits (such as those commonly used in installations of the "neon" sign tube type), but continue to operate with abnormal heating of all metal parts of the electrode. The continued overheating of the electrode may result in violent failure (such as shattering of the envelope) or damage to the socket.

One of the objects of our invention is to prevent such continued overheating of the electrode by extinguishing the discharge. According to our invention this is accomplished by utilizing the abnormal heat to effect introduction into the envelope of an atmosphere which is capable of quenching the discharge, or to put it another way, an atmosphere which is incapable of supporting a discharge between the electrodes. Further objects and advantages of our invention will appear from the following detailed description of species thereof and from the drawing.

In the drawing, Fig. 1 is a sectional view of one end of a gaseous electric discharge lamp embodying our invention; Fig. 2 is a partial section of a modification, the left hand end of the lamp being shown as rotated about its longitudinal axis somewhat as compared to its right hand end; and Fig. 3 is a sectional view of one end of a further modification.

Referring to Fig. 1, the lamp shown therein is of the positive column type comprising an elongated tubular glass envelope 1 which may be coated interiorly with a suitable fluorescent material and which contains a suitable gaseous atmosphere, such for example, as a few millimeters of argon and a small quantity of mercury. A terminal contact member in the form of a disc or cap 2 of sheet metal, such as a chrome-iron alloy known as "Allegheny 55," is sealed by fusion directly to each end of the envelope. The form of disc illustrated is like that disclosed in Patent 2,146,579, G. E. Inman, wherein the disc is inwardly embossed at 3, and is provided with an aperture 4 through which the envelope is exhausted and then filled with its gaseous atmosphere through a glass exhaust tube, the said aperture being subsequently sealed by the residue 5 of the exhaust tube.

2 At each end of the envelope is an activated filamentary electrode 6 consisting, preferably, of a coiled tungsten wire activated by a coating of alkaline earth oxides. The electrode 6 is supported from and electrically connected to the disc 2 by a comparatively rigid wire 7 one end of which is coiled around the embossment 3, as shown at 8. If desired the end 8 of the wire 7 may be welded to the disc 2. The other, or free, end 9 of the wire 7 is shaped in the form of a U which preferably lies in a plane including the longitudinal axis of the envelope 1. The extremity 10 of the wire 7 is formed into a hook 10 in which one end of the electrode 6 is clamped, while an intermediate portion thereof is doubled back upon itself in an S-shape to form a hook 11 in which the other end of the electrode is clamped.

The U-shaped portion 9 of wire 7, together with the electrode 6, thereby form a closed loop, so that when the end of the lamp is inserted in the coil of a high frequency oscillator, the loop permits the induction of currents sufficient to heat the electrode 6 and activate it by converting the original coating of alkaline earth carbonates to the corresponding oxides, preferably during evacuation of the envelope. The loop is located in the lamp in a plane perpendicular to the high frequency field. When necessary, a small wire 12 is threaded through the electrode coil to reduce the resistance of that part of the loop to a value only slightly higher than that of the remainder of the loop.

The lamp is operated by connecting it across any suitable source of electric energy which, for long lamps, may be a high voltage transformer such as those commonly used in "neon" sign type installations. The discharge strikes through the gaseous filling between the electrodes 6 at the

ends of the envelope. The electrodes are rapidly heated by the discharge to an electron-emitting temperature. As long as the electrodes remain properly activated, the ends of the lamp are not unduly heated. However, when an electrode 6 becomes deactivated by loss of activating oxides, although the current remains substantially the same, the voltage drop in the discharge increases with a resulting increased wattage, and the support wire 7 becomes highly heated, with the result that the envelope 1 may crack and be shattered, or sufficient heat may be conducted through the disc 2 to fuse it to the socket in which the lamp is mounted, or otherwise damage the socket.

According to this invention, such action is eliminated by introducing into the lamp a gas capable of extinguishing the discharge therein. In the form shown in Fig. 1, we provide within the envelope, a sealed ampule or capsule 13 which is attached to the support wire 7 by a wire 14. The ampule 13 is made of a material, or of such form (a locally weakened portion, for example), that it is ruptured upon continued overheating of the electrode and its supporting structure, thereby evolving a gas capable of extinguishing the discharge in the lamp. To this end, the ampule may be made of a glass which softens at the abnormally high temperature then existing in the lamp.

The ampule 13 may be filled with an inorganic material which decomposes at the temperature of the electrode and its supporting structure after deactivation of the electrode. The ampule is then submitted to high pressure, and by selecting a glass for the ampule which softens at those high temperatures, the ampule will open and introduce the products of decomposition into the arc stream to extinguish the discharge.

As an inorganic filling material for the ampule 13, we prefer at present to use the ammonium sulphate $(\text{NH}_4)_2\text{SO}_4$. However, we have successfully used ammonium acetate, $\text{NH}_4\text{C}_2\text{H}_3\text{O}_2$; ammonium phosphate, $(\text{NH}_4)_2\text{HPO}_4$; and sodium bisulphate, NaHSO_4 . These substances are effective even in lamps operating on high voltage circuits. It will be noted that these substances are characterized by the fact that they break down to form water vapor as one of the products of decomposition. However, in lamps operated on low voltage circuits, successful results may be obtained with gaseous fillings such as hydrogen, air, CO_2 , Cl_2 , and SO_2 .

The left hand end (not shown) of the lamp shown in Fig. 1 may be of the same construction as the right hand end with the exception that the corresponding disc 2 need not be provided with an exhaust aperture 4 and tubulation 5.

In the form shown in Fig. 2, the right hand end of the lamp is provided with an internal tubular glass appendage 15 which is sealed at its inner end but has its outer end in communication with the atmosphere. Although the appendage may be attached to the envelope 1, we prefer to fuse its outer end to the disc 2 around the aperture 4. An intermediate portion of the wire 7 is coiled around the appendage 15. The left hand end of the lamp contains a similar appendage 15 which is fused around a supplementary aperture 4' in disc 2, since that end of the lamp is evacuated through aperture 4, although, of course, the appendage could be attached around aperture 4 and the exhaust tube around aperture 4'.

In the Fig. 2 lamp, deactivation of an electrode 6 with resultant overheating, causes an append-

age 15 to be punctured, usually at a point under a portion of the wire 7 in contact therewith, thereby admitting the ambient atmosphere into the envelope with the result that the discharge is extinguished.

In Fig. 3 the lead-in wire 7 is provided with a bent V-shaped portion 16 with its bight engaging the wall of the envelope 1. In this case, overheating of the electrode 6 and wire 7 causes the envelope 1 to be punctured at the point engaged by the portion 16 of wire 7, thereby admitting air into the envelope to extinguish the discharge. A number of tests have demonstrated that a small puncture is produced in this way without shattering the envelope or cracking it around its circumference.

It will be apparent to those skilled in the art that various modifications, omissions and substitutions may be made within the scope of our invention. We have successfully applied the invention, as illustrated in the several modifications disclosed herein, to elongated tubular fluorescent lamps of the low pressure mercury vapor type which operate at low temperatures.

What we claim as new and desire to secure by Letters Patent of the United States is:

1. A gaseous electric discharge lamp comprising a sealed glass container containing spaced electrodes at least one of which is activated, said container being subject to uncontrolled fracture upon overheating at the activated electrode due to deactivation thereof, and means sensitive to such overheating and effective to cause introduction into the container, prior to such uncontrolled fracture thereof, of a gaseous material having a quenching effect upon the discharge.

2. A gaseous electric discharge lamp comprising a sealed glass container containing spaced electrodes at least one of which is an activated thermionic electrode carried by a lead-in conductor, said container being subject to uncontrolled fracture upon overheating at the activated electrode due to deactivation thereof, and means including said lead-in conductor for effecting introduction into the container, upon overheating of said conductor and prior to such uncontrolled fracture thereof, of a gaseous material having a quenching effect upon the discharge.

3. A gaseous electric discharge lamp comprising a sealed container containing spaced electrodes at least one of which is activated, and an ampule adjacent the activated electrode and sealed from the atmosphere within said container but rupturable upon overheating at said electrode due to deactivation thereof to release a gaseous material having a quenching effect upon the discharge.

4. A gaseous electric discharge lamp comprising a sealed container containing spaced electrodes at least one of which is activated, and an ampule adjacent the activated electrode and sealed from the atmosphere within said container but rupturable upon overheating at said electrode due to deactivation thereof and containing an inorganic salt which decomposes to yield a gaseous material having a quenching effect upon the discharge.

5. A gaseous electric discharge lamp comprising a sealed container containing spaced electrodes at least one of which is activated, a support wire for said electrode, an internal hollow appendage on said container sealed from the atmosphere within the container but open to the external atmosphere, a portion of said support wire being in engagement with said appendage

and adapted to puncture said appendage upon overheating thereof due to deactivation of the electrode to admit the surrounding atmosphere into the lamp and thus quench the discharge therein.

6. A gaseous electric discharge lamp comprising a sealed glass envelope containing spaced electrodes at least one of which is activated, and a support wire for said electrode having an intermediate portion thereof bent so that its bight engages the envelope wall and is adapted to puncture said wall upon overheating of said wire due to deactivation of said electrode.

7. A gaseous electric discharge lamp comprising a sealed container containing spaced electrodes at least one of which is activated, supports for said electrodes, said container being subject to uncontrolled fracture upon overheating at the activated electrode due to deactivation thereof, and means associated with the activated electrode support and operable upon overheating of the said electrode and its support due to deactivation of an electrode for introducing into the discharge path, prior to such uncontrolled fracture of the container, a gaseous material having a quenching effect upon the discharge, said means comprising a hollow glass chamber within said container capable of releasing such gaseous material but sealed from the atmosphere in said container and located in heat receiving relation to the activated electrode support to be ruptured by heat therefrom.

8. A gaseous electric discharge lamp comprising a sealed container containing spaced electrodes at least one of which is activated, and a sealed ampule adjacent the activated electrode and rupturable upon overheating at said electrode due to deactivation thereof and containing an ammonium salt which is stable at the normal operating temperature of the lamp but upon such overheating decomposes to yield a gaseous material having a quenching effect upon the discharge.

9. A gaseous electric discharge lamp comprising a sealed container containing spaced electrodes at least one of which is activated, and a sealed ampule adjacent the activated electrode and rupturable upon overheating at said electrode due to deactivation thereof and containing ammonium sulphate salt which decomposes to yield a gaseous material having a quenching effect upon the discharge.

10. A gaseous electric discharge lamp comprising a sealed container containing spaced electrodes at least one of which is an activated thermionic electrode, and a sealed ampule containing

a compound which is stable at the normal operating temperature of the lamp but which decomposes at higher temperatures to yield a gaseous material having a quenching effect on the discharge in the lamp, said ampule being located adjacent the activated electrode and being rupturable upon overheating at said electrode due to deactivation thereof.

11. A gaseous electric discharge lamp comprising a sealed container containing spaced electrodes at least one of which is an activated thermionic electrode carried by a lead-in wire, and a sealed ampule containing a compound which is stable at the normal operating temperature of the lamp but which decomposes at higher temperatures to yield a gaseous material having a quenching effect on the discharge in the lamp, said ampule being mounted on said lead-in wire adjacent the activated electrode and being rupturable upon overheating at said electrode due to deactivation thereof.

12. A gaseous electric discharge lamp comprising a sealed tubular glass container having sheet metal terminal members sealed to its ends and constituting the end walls therefor, an activated thermionic electrode at each end of the container carried by a lead-in conductor mounted on the adjacent terminal member, and a sealed ampule containing a compound which is decomposable at temperatures above the normal operating temperature of the lamp to yield a gaseous material having a quenching effect on the discharge in the lamp, said ampule being located adjacent the activated electrode and rupturable upon overheating at said electrode due to deactivation thereof.
